UNITED STATES PATENT OFFICE.

JOHN WYCKOFF METTLER, OF EAST MILLSTONE, NEW JERSEY, AND JOSEPH HAAS AND RUSSELL EVANS, OF MARTINSBURG, WEST VIRGINIA, ASSIGNEES TO THE INTER-WOVEN MILLS, INC., OF NEW BRUNSWICK, NEW JERSEY, A CORPORATION OF NEW JERSEY.

HOSIERY.

Application filed September 24, 1927. Serial No. 221,666.

Our invention consists in the novel features hereinafter described, reference being had to the accompanying drawings which illustrate several embodiments of the invention, selected by us for purposes of illustration, and the said invention is fully disclosed in the following description and claims.

The toe portion of a stocking is tapered from its junction with the foot portion to the tip, and in both seamless and full fashioned stockings there is a line of what we term selavage stitches at each side of the toe portion, one of which usually comes into contact with the tender skin at the side of the great toe a little back from the front end or tip of the toe when the stocking is worn. This side portion of the great toe is subjected to greater pressure from the shoe, than other portions of the great toe and anything which increases the size or thickness of the line of selavage stitches, will produce a rough line or ridge which will irritate this tender portion of the great toe and cause great discomfort. Any reinforcement of the toe of a stocking which extends laterally from selavage to selavage, will therefore tend to increase the bulk of the line of selavage stitches and result in discomfort to the wearer. It also follows that if the stocking toe is reinforced throughout its length, or throughout the length of the top portion, the resulting heavier fabric, if made heavy enough for protection at the point engaged by the toe nail, would be apt to irritate the tender skin on the knuckle portions of the toe of the wearer.

The object of our invention is to provide the toe portion of a stocking with a local reinforced portion of heavier and firmer fabric than the other portions of the toe, the said local reinforced portion being located on the upper side of the toe portion of the stocking, and having a width less than the distance between the lines of selavage stitches at the sides of the toe portion and extending from the tip of the toe portion rearwardly a distance less than the length of the toe portion, so that while said local reinforced portion may be made sufficiently thick and firm to prevent injury to the toe portion of the stocking by the toe nails of the wearer and especially the nail of the great toe, it will not extend down alongside of the toes nor increase the thickness of the selavage stitches

at the sides of the toe portion and will not extend rearwardly far enough to produce irritation of the toe knuckles, so that while the wearing qualities of the stockings are increased, there is no danger of irritating the tender portions of the foot which are subjected to the greatest rubbing pressure of the shoe, and particularly the side of the great toe at the inner side of the foot a short distance back from the ball of the toe, which is specially subject to rubbing pressure from the shoe.

Our invention is applicable both to seamless and full fashioned stockings, whether knit by hand or by a knitting machine, and is particularly applicable to machine knit seamless stockings. The additional local reinforced portion, or local heavier fabric, on the upper side of and at the point of the toe, is preferably produced by the introduction of an additional continuous thread in a manner similar to the introduction of a plating thread, and which may be in fact a plating thread, which is carried across the toe in opposite directions, preferably a distance less than the distance between the lines of selavage stitches, and fed with the other thread or threads used in forming the toe to those needles only which knit the local reinforced or heavier toe tip portion on the small part of the top only, of the toe portion which it occupies. This avoids the formation of float threads to be subsequently cut out, and prevents any loose or cut ends at the opposite lateral edges of the local reinforced portion, either inside of or outside of the stocking, which are always objectionable.

In the accompanying drawings,

Fig. 1 is a side elevation of a boarded and finished seamless half hose having our invention embodied therein.

Fig. 2 is an enlarged view of the toe portion and adjacent foot portion thereof.

Fig. 3 is a top plan view of the toe portion of the stocking shown in Figs. 1 and 2, before boarding.

Fig. 4 is a similar plan view showing a slight modification.

Fig. 5 is a similar view showing our invention embodied in a full fashioned stocking.

In Figs. 1, 2 and 3, we have shown our invention embodied in a seamless half hose

illustrated in its entirety in Fig. 1, in which, 1, represents the usual ribbed top, 2, the leg of the stocking, having the usual "high spliced" portion 3. 4 represents the heel 5 pocket, usually of heavier fabric than the leg, 5, the top portion of the foot, 6, the sole portion of the foot, which may be of heavier fabric than the top of the foot and leg portion, the top and sole of the foot being pref- 10 erably provided with a circular toe band, 7, extending entirely around the foot and of heavier fabric than the top portion of the foot, to facilitate the toe joining, and 8, represents the toe pocket, of heavier fabric 15 than the top of the foot, and at least as heavy a fabric as the toe band. The toe pocket of a seamless stocking is produced by knitting a plurality of half or partial courses by reciprocating knitting, on a portion only of the full circle of needles, while 20 the remaining portion of the needles are thrown out of operation and hold their stitches, and gradually narrowing the reciprocating courses to the point of the toe, indicated at 9, at which point the narrowest course or courses occur, and then knitting a substantially equal number of courses which are gradually widened; and the stocking is completed by looping a widened 25 course containing the same number of stitches as the last course of the top of the foot (or the toe band if the latter is employed) to produce the toe joining, indicated at 10. The portion of the toe pocket 30 forming the top portion thereof is indicated at 8^a, and it is this portion only which is proposed to locally reinforce in carrying out our invention.

This top portion of the toe pocket is 40 bounded on each side by a line of selvage stitches, indicated by the dotted lines, 12, 12, where the end stitches of the narrowed and widened courses are united, and if both the top and bottom portions of the toe 45 pocket were to be made of fabric sufficiently heavy to certainly withstand the wear of the toe nails against the upper part, these stitches, which we will term the selvage stitches of the toe, would produce a rough 50 line, which would be very likely to irritate the tender skin at the side of the great toe, a little back from the end of the toe, which is particularly sensitive to such irritation, and particularly subject to rubbing pressure 55 from the shoe.

In the embodiment of our invention shown in Figs. 1, 2 and 3, the top portion, 8^a, of the toe is shown provided with a locally reinforced portion of heavier and firmer fabric 60 for a number of courses extending back from the "point" or narrowest course or courses of the toe pocket, a portion only of the distance to the toe joining, and being of a width less than the distance between the 65 lines of selvage stitches, 12. This produces

the local reinforcement, indicated by the most heavily shaded portions of the toe in Figs. 1, 2 and 3, and comprising a central panel portion extending from the toe tip, 9, back part way only toward the toe joining, and being much narrower than the top of the toe pocket, and having its lateral edges, 11^a, at a distance from the adjacent line of selvage stitches and its rear edge, 11^b. 70

This extra local reinforcement is preferably formed by introducing an extra thread, which may be a plating thread, along with the thread or threads knitting the courses of the top of the toe and feeding the extra thread in opposite directions in alternating courses, in the centrally located stitches only of one course, in one direction, and in the centrally located stitches of the next course in the opposite direction, and so on until the panel, 11, is completed and then 80 knitting the remaining courses of the top of the foot without said extra reinforcing or plating thread. The extra plating or reinforcing thread is therefore continuous throughout the locally reinforced portion, 90 and there are no float threads to be cut and no loose ends at any point in the lateral edges of the panel, or lateral extensions. 85

The use of a local reinforcement in the form of a panel extending less than all the 95 way across the toe from selvage to selvage, permits of the use of a heavier reinforcing, throughout the panel, or of knitting it with a tighter stitch, or both, resulting in the formation of a panel of firmer, harder, wear 100 resisting fabric at the point of greatest wear than would be possible if it were carried all the way across from one line of selvage 105 stitches to the other, in a seamless stocking, and for the full width between the selvages of the inset sides of the toe of a full fashioned stocking. Such a heavy fabric if knit from selvage to selvage and carried back far enough along the selvages to furnish ample 110 protection for the toe of the stocking, would form a very irritating ridge at each side, portions of which a short distance back from the tip of the toe of the stocking would seriously irritate the sides of the toes of the wearer, as previously stated, and if knit for 115 the full length of the toe, would provide an unnecessarily firm hard fabric over the toe knuckles tending to produce irritation thereof, and also add in the case of seamless hose, an objectionable ridge across the top 120 of the toes at the toe joining, indicated at 10. These objectionable features are entirely avoided by our invention.

The local reinforced portion or panel, 11, is preferably of approximately the width of 125 the toe tip at the narrowest course or courses, indicated at 9, but it may be of slightly less or slightly greater width. We prefer to make it as indicated in Fig. 3, of slightly less width than the length of the narrowest 130

course or courses of the toe, so that the lateral edges, 11^a, of the panel are separated a distance from the adjacent lines of selvage stitches, 12, throughout the entire length of the panel. This is particularly desirable in seamless stockings, as it facilitates introduction and removal of the reinforcing or plating thread or threads, in knitting the courses of the panel adjacent to the point of the toe.

Where it is desired to make the local reinforcement or panel of a width equal to or slightly greater than the length of the narrowest course or courses at the toe tip, the extra reinforcing thread or threads may be introduced in all the stitches of a few courses of the top portion of the foot immediately adjacent to the tip of the toe, that is, immediately adjacent to the narrowest course or courses of the toe, after which the extra thread or threads is introduced into the centrally located stitches only of succeeding courses to form the panel with its lateral edges well removed from the lines of selvage stitches. In Fig. 4 of the drawing, we have shown such a construction, the various parts of the toe illustrated in said figure which correspond with those in the preceding figures being given the same reference numerals with the addition of 100. In this figure it will be seen that a few courses immediately adjacent to the tip of the toe are carried from selvage to selvage, after which the lateral edges, 111^a, are stepped in and the reinforcing thread is confined to a certain number of centrally located stitches in each of the succeeding courses, so that the lateral edges of the panel are well removed from the lines of selvage stitches. In this construction the panel, 111, is provided immediately adjacent to the point of the toe with small triangular lateral extensions, indicated at 111^c, which terminate at the course indicated at 111^d, beyond which the panel is knit in the centrally located stitches only of succeeding courses. The presence of these small triangular extensions immediately adjacent to the toe tip and the resulting thickening of a few of the selvage stitches immediately adjacent to the toe tip is not seriously objectionable, as these stitches would not come in contact with the rounded out portion of the great toe a distance back from the extreme tip, and along the inner edge of the foot, which is exposed to side pressure from the cap of the shoe. As the courses adjacent to the tip of the toe are progressively widened, this construction permits of making the succeeding courses of the panel, 111, of a width equal to or greater than the length of the narrowest course or courses at the toe tip and still leave room at each side of the panel to facilitate the introduction and removal of the extra reinforcing or plating thread or threads, and the lateral edges, 111^a, being at a distance from the adjacent portions of the

selvage stitches, these stitches which extend along the tender part at the side of the great toe before referred to will not contain the reinforcing or plating thread, and will not be affected by the local reinforcement, and consequently cannot produce irritation of the foot. The rear edge, 111^b, of the panel terminates as previously described with reference to the other figures at a considerable distance from the toe joining indicated at 110, so that the panel may be made sufficiently heavy and firm to protect the stocking at its point of greatest wear from the toe nails without danger of producing irritation of the foot.

With our invention it would be possible to knit a stocking without making the bottom portion of the toe and the top portion thereof, exclusive of the described panel, of heavier fabric, and it is unnecessary in any case to make such parts of the toe portion of the stocking, exclusive of the described panel, heavier than the fabric of the sole of the stocking and toe band, unless it is particularly desired, although this may be done where it is desired or necessary for other reasons. The actual wear on the bottom portion of the toe of the stocking is much less than that on the top of the toe, where it is exposed to the action of the toe nail, which latter wear is fully taken care of by the described panel of heavier fabric.

Our invention is also applicable to full fashioned or straight knit stockings, and it will be understood that it is applicable to the toes of all varieties of seamless and full fashioned stocking, whether half hose or full length hose, and regardless of the material with which they are made. In Fig. 5 we have shown the toe portion of a full fashioned stocking, indicated at 208, the top portion, 208^a, of which is provided with the panel, 211, of heavier fabric, extending from the narrowest course or courses at the point of the toe, indicated at 209, rearwardly a distance considerably less than the length of the upper portion of the toe, the panel being in this instance of less width than the narrowest course or courses of stitches at the point of the toe, and having its lateral marginal edges, 211^c, entirely removed from the selvages of the inset sides of the top of the toe, indicated in dotted lines at 212, so that the selvage stitches are not thickened or roughened by the additional plating or reinforcing thread, which is knit into the stitches of the heavier panel, 211, through the centrally located stitches of each course of the panel, in the same manner as hereinbefore described, that is to say, the said reinforcing thread or plating thread is continuous throughout the panel, and extends in opposite directions through the stitches of alternate courses in knitting the top portion of the toe.

Our invention can be carried into effect either by knitting the stockings by hand, and introducing the additional reinforcing or plating thread in the stitches of certain courses or part of the courses of the top of the toe portion only, in the manner previously described, to form the described panel, or by knitting the stockings on a suitable knitting machine and providing it with an auxiliary thread guide of special design carrying the reinforcing or plating thread, and capable of being moved by hand or otherwise into and out of operative position with respect to those needles which knit the panel of the heavier fabric, in the top portion of the toe. Such additional thread guide may be so manipulated by hand, or they may be operated automatically under the control of suitable pattern mechanism. For example the invention may be carried into effect for the production of a seamless stocking embodying our invention, by the employment of the well-known Hemp-hill knitting machine, shown for example in Letters Patent of the United States, No. 933,433, dated September 7, 1909, by providing an extra thread guide for feeding the extra reinforcing or plating thread during the formation of the panel of heavier fabric, in the upper portion of the toe pocket, if desired, which may be thrown into or out of operation by hand at opposite sides of the panel. One form of apparatus by which our invention may be carried into effect is shown and described in an application of Joseph Haas and Russell Evans, filed in the United States Patent Office, on or about the 14th day of November, 1927, and given Serial No. 233,145, but our invention may also be carried into effect by other means, if desired.

What we claim and desire to secure by Letters Patent is:-

1. As a new article of manufacture, a stocking having the upper portion of the toe provided with a panel of heavier fabric extending from the point of the toe rearwardly, portions of said panel being of less width than the upper portion of the toe and having their lateral edges separated a distance from the lateral edges of the toe.

2. As a new article of manufacture, a stocking having the upper portion of the toe provided with a panel of heavier fabric extending from the point of the toe rearwardly a distance less than the length of the top portion of the toe, said panel having portions of less width than the upper portion of the toe and having its lateral edges separated a distance from the lateral edges of the top portion of the toe.

3. As a new article of manufacture, a stocking having the upper portion of the toe provided with a panel of heavier fabric extending from a point adjacent to the point

of the toe rearwardly a distance less than the length of the toe portion of the stocking, portions of said panel having a substantially uniform width considerably less than the width of the toe portion of the stocking, and having their lateral edges separated a distance from the lateral edges of the toe portion.

4. As a new article of manufacture, a stocking having the upper portion of the toe provided with a panel of heavier fabric extending from a point adjacent to the point of the toe rearwardly a distance less than the length of the toe portion of the stocking and having portions of substantially uniform width less than the width of the toe portion of the stocking and having substantially parallel lateral edges separated a considerable distance from the lateral edges of the top portion of the toe, the stitches forming said panel containing a continuous extra thread, or threads extending through alternate courses of the stitches of said panel in opposite directions.

5. As a new article of manufacture, a seamless stocking including selvage stitches uniting the upper and lower portions of the toe pocket and having the upper portion only of the toe pocket provided with a panel of heavier fabric extending from a point adjacent to the narrowest course or courses of the toe pocket toward the toe joining and being of less length than the upper portion of the toe pocket, said panel having portions of considerably less width than the upper portion of the toe pocket, provided with substantially parallel edges separated a distance from the adjacent line of selvage stitches which unite the upper and lower portions of the toe pocket.

6. As a new article of manufacture, a stocking having the upper portion of the toe provided with a panel of heavier fabric extending from a point adjacent to the point of the toe a distance back less than the length of the upper portion of the toe and comprising a few courses adjacent to the point of the toe extending entirely across the toe, the remaining courses of said panel being of less length than the length of the corresponding courses of the toe portion, and the lateral edges of said panel in rear of the courses which extend entirely across the toe being separated a distance from the adjacent lines of selvage stitches.

7. As a new article of manufacture, a seamless stocking including selvage stitches uniting the upper and lower portions of the toe pocket and having the upper portion of the toe pocket provided with a panel of heavier fabric extending from a point adjacent to the narrowest courses of the toe toward the toe joining a distance less than the length of the upper portion of the toe pocket, said panel comprising a small number of courses

of stitches adjacent to the narrowest courses of the toe, extending substantially the full width of the upper part of the toe, the other courses of stitches of said panel being located substantially centrally of the upper part of the toe pocket and being of less length transversely of the panel than certain courses of the panel immediately adjacent to the tip of the toe and of less length than the corresponding courses of the upper portion of the toe pocket, the lateral edges of the narrower portion of said panel being substantially parallel and separated a distance from the adjacent lines of selvage stitches which unite the upper and lower portions of the toe pocket.

8. As a new article of manufacture, a seamless stocking including selvage stitches uniting the upper and lower portions of the toe pocket and having the upper portion of the toe pocket provided with a panel of heavier fabric extending from a point adjacent to the narrowest courses of the toe toward the toe joining a distance less than the length of the upper portion of the toe pocket, said panel comprising a small number of courses

of stitches adjacent to the narrowest course of the toe, extending substantially the full width of the upper part of the toe, the other courses of stitches of said panel being located substantially centrally of the upper part of the toe pocket and being of less length transversely of the panel than certain courses of the panel immediately adjacent to the tip of the toe and of less length than the corresponding courses of the upper portion of the toe pocket, the lateral edges of the narrower portion of said panel being substantially parallel and separated a considerable distance from the adjacent lines of selvage stitches which unite the upper and lower portions of the toe pocket, the stitches forming said panel containing an additional continuous thread or threads extending in opposite directions through the stitches in alternate courses of the panel.

In testimony whereof we affix our signatures.
